(57) **CLAIM**

The ornamental design for a display screen with graphical user interface window, as shown and described.

DESCRIPTION

FIG. 1 is a front view of a display screen, or portion thereof. FIG. 2 is a front view of a second embodiment thereof; and, FIG. 3 is a front view of a third embodiment thereof. The dash-dash broken lines in the drawings form no part of the claimed design. The dot-dash broken lines at the periphery in all views represent the boundary lines of the claimed design and a computer display screen, wherein the computer display screen forms no part of the claimed design.
